UNITED STATES PATENT OFFICE.

SAMUEL L. BELKNAP, OF LOS ANGELES, CALIFORNIA, ASSIGNOR TO IN-A-WALL SAFE COMPANY, INC., OF LOS ANGELES, CALIFORNIA, A CORPORATION OF CALIFORNIA.

WALL SAFE.

Application filed August 24, 1925. Serial No. 52,012.

This invention relates to improvements in wall safes.

Heretofore safes have been provided which are adapted to be built into or imbedded in walls of dwellings and the like, which require a special wall construction or a special mounting for supporting them within the walls.

An object of this invention is to provide a wall safe which does not require the special mounting or special wall construction, but which is so constructed that it may be readily mounted between the conventional studs employed in building the wall.

Another object of this invention is to provide a wall safe which is of strong and rugged construction and which is fire proof so that in case of fires the contents of the safe will not be damaged.

A further object of this invention is to provide a wall safe consisting of a receptacle adapted to be imbedded into a wall between two studs thereof, and which is so constructed that its forward face will be flush with the plaster surface, the receptacle being formed of sections of sheet steel welded together and having inner and outer walls between which asbestos or equivalent heat insulating material is disposed.

With the foregoing and other objects in view which will be made manifest in the following detailed description and specifically pointed out in the appended claims, reference is had to the accompanying drawings for an illustrative embodiment of the invention, wherein

Figure 1 is a front elevation, parts being broken away and shown in section, of the improved wall safe,

Fig. 2 is a vertical section taken substantially on the line 2—2 of Fig. 1,

Fig. 3 is a vertical section taken on the line 3—3 of Fig. 2, and

Fig. 4 is a perspective view of one of the inner receptacles adapted to be disposed within the wall safe.

Referring to the accompanying drawings wherein similar reference characters designate similar parts throughout, the wall is shown as being formed of studs S against which are fastened laths L, on which the plaster P is disposed. In practically all dwellings the studs S are of one or two con-

ventional sizes, namely being formed of wood and being commonly called 2 x 4 or 2 x 3. 55 The actual width of a 2 x 4 in practice is 3 3/4 inches, and the actual width of a 2 x 3 is 2 3/4 inches. The conventional thickness of the plaster P and the lath L is 3/4 inch. Therefore, the improved wall safe is made 60 in either of two sizes, which have outside thickness dimensions which are 4 1/2 inches and 3 1/2 inches respectively, so that when the wall safes are mounted between the studs, the back of the safe will be even with the 65 backs of the studs and the forward face of the safe will be flush with the plaster. The studs S are spaced apart usually certain conventional distances, that which is most commonly used being a distance of fourteen 70 inches between the centers of the studs. The improved wall safe has its outside width dimension equal to the distance between two adjacent studs. Consequently, when the safe is imbedded or mounted within the wall, 75 it snugly fits between two studs, so that no special wall construction is required to support it, and if it is desired to mount the safe in the wall of a dwelling which has already been built, it is only necessary to 80 tear out the plaster and lath between two adjacent studs to permit the reception of the safe.

The details of the construction of the safe are as follows: An outside back wall 10 is 85 provided which is formed of sheet steel and has its top, bottom and side edges bent forwardly, as indicated at 11. Top, bottom and side outside walls are provided, as indicated at 12, these walls being also formed of sheet 90 steel and being formed of separate pieces. They have their rearward ends positioned within the forwardly turned edges on the back wall. Intermediate top, bottom and side walls 13 are positioned parallel to and 95 within the outside walls 12. These intermediate walls are formed of separate pieces of sheet steel and are in spaced relation to the outside walls. They have their rearward edges abutting against the outside back wall 100 10. The inside walls 14 are formed of sections of sheet steel having their rearward edges abutting against the outside back wall and are parallel to, but in spaced relation to the intermediate walls 13. The forward edges of the inside walls 14 are bent 105

toward the intermediate walls 13 so as to engage them and then are bent forwardly and over the edges of the intermediate walls, engaging the inside surfaces of the outer

5 walls and then being bent around the forward edges of the outer walls 12. The portions 15 of the inner walls 14, which are bent rearwardly from the outer surfaces of the outside walls 12, are extended rearwardly 10 a distance equal to the thickness of the plaster P and the lath L so that the edges of these portions will abut against the forward faces of the studs S.

Forwardly of the outside back wall 10 15 there is disposed an inside back wall 16 which has its edges abutting the inside walls 14. Between the outside back wall 10 and the inside back wall 16 there is disposed asbestos or similar heat insulating material, 20 and asbestos is also disposed between the outside walls 12 and the intermediate walls 13 and between the intermediate walls 13 and the inside walls 14. The edges 11 of the back wall 10 are spot welded to the outside 25 walls 12, and the edges of the inside walls 14 and the intermediate walls 13, which engage the outside back wall 10 are spot welded to it. In a similar manner the portions 30 of the inside walls 14, which engage the intermediate walls 13 and the outer walls 12, are spot welded to them, and the meeting edges of the sections forming the various 35 walls are spot welded together. The edges of the inner back wall 16 are welded to the inside walls 14.

A door is provided for the safe which is hinged to the receptacle as by a hinge 17. This door is provided with a suitable lock 18 which may be either key operated or a 40 combination lock having a suitable bolt adapted to be caused to engage a keeper 19 on the side of the receptacle. The door consists of an outside front wall 20, an intermediate front wall 21 and an inner front 45 wall 22. The edges of the outer front wall 20 are bent backwardly over the edges of the intermediate front wall 21 and over the edges of the inner front wall 22, and are spot welded thereto. In this manner a 50 stepped or rabbeted edge is provided on the door complementary to the stepped edge on the top, bottom and side walls of the receptacle. Asbestos or similar insulating material is disposed between the outside and intermediate front walls 20 and 21, and between the inside and intermediate front 55 walls.

The receptacle is mounted between the studs by means of screws 23 which are driven through the side walls into the sides 60 of the studs. Suitable cover members 24 are pivoted upon the inside walls 14 of the receptacle and are adapted to cover the heads 65 of the screws, preventing any fire from entering the safe in case of fire, and prevent-

ing the screws from dropping into the interior of the safe if the studs should be burned away.

Upon the inside of the receptacle there are mounted small angles 25 which are arranged to support shelves 26 between them. An inner box or receptacle is provided for the safe which may be positioned therein, one of these boxes being shown in Fig. 4. Each box is rectangular in form and has a hinged cover. Each of the boxes is formed of inside and outside walls of sheet steel, these walls being connected together and having asbestos or other insulating material disposed between them. They may be provided with locks 27, as shown upon the drawing.

From the above it will be appreciated that an improved wall safe is provided which can be easily and quickly mounted between the conventionally spaced studs of the wall in a building, and which will have its outer face assume a position flush with the plaster, so that a tapestry or picture may be hung over it. Furthermore, it is practically impossible to detach the safe from the wall after it has once been applied without opening the door, and furthermore, the safe is absolutely fire proof, so that no papers within the safe will be burned in case of fire.

It will be understood that various changes in the detail of construction may be made without departing from the spirit or scope of the invention as defined by the appended claims.

I claim:

1. A wall safe comprising a rectangular receptacle having an outside width dimension equal to the distance between two wall studs, said receptacle having inner and outer walls, an insulating material disposed between the walls, there being apertures formed in the inner and outer walls and through the insulating material at the sides of the receptacle, whereby securing elements may be driven through the sides of the receptacle and into the wall studs, and pivoted members disposed upon the inside of the inner walls adapted to cover the ends of said securing elements.

2. A wall safe comprising a receptacle having outer back, top, bottom and side walls, intermediate top, bottom and side walls extending from the outer back wall toward the front but having their forward edges disposed rearwardly of the forward edges of the outer top, bottom and side walls, inner top, bottom and side walls extending forwardly from the outer back wall, the forward portions of the inner walls being bent against their respective intermediate walls and across the forward edges of the intermediate walls and being bent against their respective outer walls, thus forming a rebated edge at the front of the receptacle,

and an inner back wall disposed between the inner top, bottom and side walls forwardly of the outer back wall, an insulating material disposed between the walls, and a door hinged to the receptacle having an outer front wall, an intermediate wall and an inner front wall, the edges of the outer

front wall being bent over the intermediate and inner walls and forming a rebated edge complementary to the rebated edge on the top, bottom and sides of the receptacle.

In testimony whereof I have signed my name to this specification.

SAMUEL L. BELKNAP.
